COMBINATION SHIPPING AND DISPLAY BOX

Walter A. Reich, Kansas City, Mo., assignor to A. Reich & Sons, Inc., Kansas City, Mo., a corporation of Missouri

Application May 5, 1955, Serial No. 35,845

Term of patent 14 years

(Cl. D58—12)

Fig. 1 is a perspective view of a combination shipping and display box shown in closed condition, showing my new design; and

Fig. 2 is a perspective view thereof, showing the cover portion removed from the box.

I claim:

The ornamental design for a combination shipping and display box, as shown.
